UNITED STATES PATENT OFFICE

CLINTON E. WOODS, DECEASED, LATE OF YEADON, PENNSYLVANIA, BY JULIA E. WOODS, ADMINISTRATRIX, OF UPPER DARBY, PENNSYLVANIA

DESIGN FOR A CASING FOR A FLOOR-POLISHING BRUSH

Application filed June 12, 1929. Serial No. 31,648. Term of patent 3½ years.

To all whom it may concern:

Be it known that CLINTON E. Woods, deceased, late a citizen of the United States, formerly residing at Yeadon, in the county of Delaware and State of Pennsylvania, invented a new, original, and ornamental Design for a Casing for a Floor-Polishing Brush, of which the following is a specification, reference being had to the accompanying drawings, forming a part thereof.

Fig. 1 is a perspective view of the article from the front showing the new design; Fig. 2 is a perspective view of the article from the side; and Fig. 3 is a perspective view of the article from a position between the front and side.

What is claimed is:—

The ornamental design for a casing for a floor-polishing brush, substantially as shown.

JULIA E. WOODS,
Administratrix of the Estate of Clinton E. Woods, Deceased.
